BRUSH

J T. Hanson, 6060 Parkdale St., Dallas, Tex.
Filed Aug. 10, 1960, Ser. No. 48,594
2 Claims. (Cl. 15—160)

This invention relates to new and useful improvements in brushes particularly, although not necessarily, for ceilings and has for its primary object to provide, in a manner as hereinafter set forth, novel means whereby swirling designs in paint and texture that have been applied to ceilings and in a thickened liquid or plastic state may be rapidly executed on the ceilings.

Another very important object of the present invention is to provide a ceiling brush of the aforementioned character which embodies unique means for pivotally anchoring the device to the work.

Other objects of the invention are to provide a ceiling brush of the character described which will be comparatively simple in construction, strong, durable, compact, of light weight and which may be manufactured at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

FIGURE 1 is a view in side elevation of a brush constructed in accordance with the present invention;

FIGURE 2 is a view in end elevation thereof;

FIGURE 3 is a fragmentary view in horizontal section through the inner end portion of the device, taken substantially on the line 3—3 of FIGURE 1; and

FIGURE 4 is a fragmentary view in vertical longitudinal section through the inner end portion of the device, taken substantially on the line 4—4 of FIGURE 3.

Referring now to the drawing in detail, it will be seen that the embodiment of the invention which has been illustrated comprises an anchoring pivot which is designated generally by reference numeral 5. The pivot 5 is engageable with the ceiling or other surface to be painted. Toward this end, the pivot 5 includes a metallic shank 6 which terminates at one end in a work penetrating point 7. Mounted on the other end portion of the shank 5 is an elongated handle 8 of wood, plastic or other suitable material.

Mounted for swinging movement on the pivot 5 is a brush 9. The brush 9 includes a back or bar 10 of suitable dimensions and material having one end portion journaled on the shank 6 at a point adjacent the handle 8. The pivoted end portion of the bar 10 has formed therein an opening 11 (see FIGURE 4) which receives the shank 6. Fixed on the shank 6 is a stop collar 12 which retains the bar 10 closely adjacent the handle 8 on said shank.

The brush 9 further includes a series of sockets 13 in the upper longitudinal edge of the bar 10. Anchored in the sockets 13 are tufts of elongated bristles 14 of suitable material, preferably broom corn which is well known

2

to be quite stiff. It will be noted that the bristles 14 parallel the shank 6 and terminate substantially flush with the point 7 thereof. Mounted on the outer or free end portion of the bar 10 is an elongated operating handle 15 which parallels the handle 8.

It is thought that the use of the device will be readily apparent from a consideration of the foregoing. Briefly, the bristles 14 may be dipped in the paint in the usual manner. However, the paint or texture is preferably applied to a ceiling by a conventional roller or spray device. Gripping the handle 8 in one hand, the operator engages the shank 6 with the work and forces the point 7 thereinto for anchoring the pivot 5. With the other hand, the operator then grips the handle 15 and swings the brush 9 in a circle around the pivot 5 for rapidly executing swirling designs in the paint or texture on the ceiling or other surface in an obvious manner.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A brush comprising an anchoring pivot including an ice pick having an elongated shank comprising a work penetrating point on one end, an elongated handle fixed longitudinally on the other end portion of the shank, a collar fixed on the shank adjacent to but spaced from said handle, a bar having one end portion journaled on the shank between the collar and the handle for swinging movement therearound, a series of equally spaced bristle tufts on the bar paralleling the shank and terminating substantially flush with said point thereof, said bristles comprising broom corn and arranged in a row extending along the entire length of said bar, said bristles being of the same length, and an elongated operating handle near the free end portion of the bar paralleling and substantially the same length as the first named handle and providing means for swinging said bar in a circular path around the pivot, said operating handle being of circular cross-section.

2. A brush as defined in claim 1 wherein said operating handle comprises a central portion of constant diameter, an enlarged head secured to one end of said central portion, the other end of said central portion being outwardly flared and secured to said free end portion of the bar.
